UNITED STATES PATENT OFFICE

125,556

DESIGN FOR A SHOE OR SIMILAR ARTICLE

Philip Aronov, Los Angeles, Calif.

Application November 24, 1939, Serial No. 88,448

Term of patent 3½ years

To all whom it may concern:

Be it known that I, Philip Aronov, a citizen of Poland, residing at Los Angeles, in the county of Los Angeles and State of California, have invented a new, original, and ornamental Design for a Shoe or Similar Article, of which the following is a specification, reference being had to the accompanying drawing, forming part thereof.

Fig. 1 is a front perspective view of a shoe showing my new design;

Fig. 2 is a rear perspective view thereof; and

Fig. 3 is a sectional view taken on line 3—3 of Fig. 2.

My design for a shoe as shown is characterized by the upper having a free edge at one side of

the shoe extending substantially upright from the midsole at about the junction of the arch and toe portions and forming the forward side of a V-shaped notch, the rearward side of the notch being formed by an adjacent free edge of the upper which slopes forwardly and downwardly to meet said upright edge substantially intermediate the height thereof, the thus formed V-shaped notch being disposed substantially above the arch portion of the midsole.

I claim:

The ornamental design for a shoe or similar article, substantially as shown and described.

PHILIP ARONOV.
